HIGH PRESSURE ROTARY PUMP UNIT

John Marco, Earlville, Md.

Application August 16, 1954, Serial No. 449,914

5 Claims. (Cl. 103—202)

This invention relates to pumping equipment and more particularly to one of the rotary type intended to be employed for high pressure duty.

Rotary pumps of the conventional type are usually employed for work at relatively low pressure, when they are of the single stage type. However, they may be used for high pressure duty if they are constructed on a multi-stage arrangement, where the pressure is increased in value by augmenting the pressures of each stage in series, until the final pressure attained is of the total required. By utilizing the pump of this invention, pressures of the order of over a 1000 lbs. per square inch may be obtained in a single stage. To accomplish this the type of pump described in United States Patent Number 2,321,609 is employed and driven through the use of a suitable motor. However, in addition to the features referred to and included in this patent, which is the invention of the applicant herein, the structure is improved by the use of an automatic seal that is designed to ride on the hub which is an integral part of the rotors, and in such a manner as to substantially eliminate the seal wear on the shafts. The pump rotor is arranged with a balancing plug that is connected with the rotor and serves to automatically balance the hydraulic stresses in the device. This will be more fully appreciated as the invention is more fully outlined.

An object of the invention is to provide a new and improved rotary pressure pump that avoids some of the objections and limitations of previous types in this class.

Another object of the invention is to provide a new and improved rotary pressure pump that will be hydraulically balanced.

A further object of the invention is to provide a new and improved rotary pressure pump that will be sealed hydraulically to substantially eliminate wear.

An additional object of the invention is to provide a new and improved rotary pressure pump including means to prevent the fluid material or product handled thereby from entering the spline sections.

A still further object of this invention is to provide a new and improved pressure pump designed to facilitate cleaning and the maintenance of sanitary conditions.

Still another object of the invention is to provide a new and improved pressure pump designed to reduce shaft corrosion, abrasion and wear to a minimum.

Another object of this invention is to provide a new and improved pressure pump that can be operated under increased tolerance yet avoid material seepage of the product in designated portions of the pump where such would be injurious or undesirable.

Further objects and advantages of the invention will be apparent from the following description, taken in conjunction with the accompanying drawings, wherein:

Fig. 1 is a longitudinal section through a rotary pressure pump embodying this invention;

Fig. 2, a plan view partly in section of Fig. 1;

Fig. 3, an elevational view looking into the pump structure where the rotors are attached to their shafts;

2

Fig. 4, a similar view with the cover and header plates removed and the sealing plugs disclosed—the rotors not being shown;

Fig. 5, a modified form of sealing plug.

5 Similar parts throughout the drawings are designated by the same reference numerals.

In the construction shown in Fig. 1, the general structure is that of a high pressure rotary pump 1, such as illustrated in United States Patent No. 2,321,609, and 10 intended primarily for high pressure duty involved during the processing of fluid material into a homogenized product in the homogenizer 2. The studs 3 secure the cover plate 4 in place, which is pressed against the flat header plate 5, and other plates as shown. The header plate 5 is primarily intended to form a close fitting abutment against which a pair of meshing rotors 6 and 7, respectively, can engage their forward faces. The plate 5 is provided interiorly with circular recesses 60 and 70 respectively in which the sealing plugs 61 and 71 rotate 15 in the rotor housing 11 in front of the rotatable shafts 8 and 9. The sealing plugs are externally screw threaded on one side so they will screw tightly into the rotors. This is facilitated by the square heads 62 and 72 on the 20 opposite sides and the enlarged circular flanges 63 and 73 extending out around the plugs 61 and 71 respectively. These plugs being sealed in, in the header plates by the closed-in structure of the recesses 60 and 70 serve to prevent seepage of the material being pumped or homogenized in the device. The recesses 60 and 70, with the plugs 61 and 71, and the shafts 8 and 9 respectively, are axially aligned with each other.

The rotor 6 is mounted on the driving shaft 8 and meshes its radially projecting blades 66 with the similar blades 77 of the driven rotor 7, so they will be cooperatively propelled, as well as serving to process and eject the fluid material used in the pump. The rotors 6 and 7 fit closely against the wall surfaces of the rotor chamber 80 and through grooves and ring slots formed therein 30 produce the necessary high pressure in the material pumped, as already described in the patent cited above.

These grooves and slots are not illustrated in the accompanying drawings. Various parts of the device having the same reference numerals in the patent cited as 35 those in this application and having the same functions, are included in the following description:

The housing for the rotor is marked 11. An automatic compensator control wear plate is shown at 12, between the header plate 5 and the front seal plate 13. 40 A companion seal plate 14 is secured between the plate 13 and the gasket plate 81, next to the flange 84 of the pump shaft housing 15, and is provided with the metal armor liners 17 in the bevelled bores 16 and chambers 16'. They cooperate with the annular seal glands 18, to 45 seal off the hubs of the rotors and thereby prevent leakage. Gasket rings 82 are inserted in annular recesses 83 in the stuffing box plate 81 about the shafts 8 and 9 to prevent leakage and in place of the type of gaskets indicated, for the same purpose, directly in the housing 15 in the previous patent already mentioned. The radially projecting keys 84 are used with the shafts 8 and 9 to 50 operably secure the rotors 6 and 7 in preference to the arrangement previously illustrated. Double sets of roller bearings 24 support the shafts 8 and 9 in the housing 15, which is interiorly enlarged for the purpose. The sleeves 55 85 retain the bearings 24 in place and are themselves held against them by the collars 86, integral with the shafts 8 and 9, as shown in Fig. 1. The shafts 8 and 9 project from the housing 15 into a bearing and gear housing 25, where they have auxiliary gears 23 keyed and mounted on them and meshing with one another. The shaft 9 terminates in the housing 25 and inside the roller 60 65 70 75 80 85 90 95 100

bearing 24 arranged for it. Another similar bearing 24 supports the drive shaft 8, which does not terminate like the shaft 9, but continues through to couple to a motor extraneous to the pump structure, and is provided with a stuffing box 88 to prevent leakage. An end plate 26 is bolted on the gear housing 25 to retain the roller bearings 24 in place and aligned. The housing 25 is bolted in place on to the housing 15 and also has an annular passage or water jacket 68 through it for cooling water to circulate.

The housing 15 is provided with an oil sump 28 and a drain connection 29 to remove the accumulations. A partition 27 runs through the housing 15 and is suitably slanted to facilitate the draining of the housings 15 and 25 to the sump 28. The outlet plugs 69, provide access to the water jacket 68. The inlet and outlet to the homogenizer are respectively shown at 35 and 36.

In the form shown in Figure 1, the sealing plugs 61 and 71 are screwed into the rotors and block the latter while riding with it, while at the same time covering the ends of the shafts 8 and 9 and the splines or keys 84 in them, so that leakage is prevented along the shafts. The flanges 63 and 73 accentuate this prevention. The recesses 60 and 70 take the place of the bores previously employed. The hubs 64 and 74 on the rotors 6 and 7 respectively, extend laterally from the rotors within holes provided therefor in the plates 12, 13 and 14 and at the inner portions run in peripheral contact with the liners 16 and glands 18. A space is left between the hub faces and the gasket plate 81 as shown. A groove 87 is left in each hub, at the corner left between each plate and its hub portion. The collars 86 on the shafts, between the sleeves 85 and the gears 24 are items not previously disclosed and serve as balancing means to damp deflections and reduce shaft breakage due to concentrated localized fatigue causing excessive shear stresses.

In the modified form shown in Fig. 5, the sealing plug 171 is of somewhat different form and is termed an automatic sealing plug. It provides greater running tolerance than the form above described. It comprises a ring-like shell 174 and at 176 is exteriorly screwthreaded to thread into the rotor 7, and has peripheral sockets 172 for the insertion of a tool to operate it, instead of the nut heads 72 previously indicated. Its flange 173 extends over and partly fits into a recess or counterbore 177, in the rotor face. The sealing plug 171 contains centrally within it, a frictionally held element 180 which is movably inserted in the circular shell 174 concentrically surrounding it and provided with a peripheral groove 178 receiving a gasket ring 179 to make it tight. The shaft 9 is preferably reduced in diameter as shown in Figure 5 with the splines 84 brought to the normal diameter of the shaft. The faces 65 and 75 of the rotors are impressed by similar pressures and enable the rotors to revolve properly balanced. The pressure on the exterior face of the plug 171 forces the element 180 against the free end face of the shaft 9. The shell 174 of the plug is secured to the rotor 7 by the screwthreads 176 and with its shoulder 173 seals off the screwthreaded sections. The gasket ring 179 prevents leakage by the element 180 and by the splines and key ways.

The invention is of particular importance, since it affords better service from a pump capable of performing high pressure duties. High pressure in any pump creates special problems. The fluids handled under high pressure tend to create excessive wear, particularly where such fluids contain abrasive or corrosive substances. Any leakage or seepage of such fluids results in the same becoming lodged within the key-ways and splines thereby causing excessive wear at these points. The sealing means of this invention substantially eliminates these undesirable features. The sealing plugs obstruct leakage by the ends of the revolving shafts and do it in a simple and effective manner. They are easily replaceable and afford a certain amount of adjustability that facilitates

their use, maintenance and assembly. They do not involve any appreciable additional cost or add to the size of the unit. It prevents the contamination of the product and its becoming involved in the mechanism of the device.

5 It will be obvious to those skilled in the art that various changes may be made in the invention without departing from the spirit and scope thereof, and therefore the invention is not limited by that which is shown in the drawing and described in the specification, but only as indicated in the appended claims.

10 What is claimed is:

1. For use in a high pressure pump of the rotary type, a rotor shaft, a rotor having a bore extending therethrough and removably received on said shaft, a portion of said rotor projecting beyond the end of said shaft and having a flat end face on the outer end thereof perpendicular to the axis of said shaft, key ways in said shaft and said rotor, a key in said key ways to prevent relative rotation between said shaft and said rotor, an enlarged threaded recess in the outer end of said bore, a sealing plug threadedly received in said recess and an annular flange on said plug engaging said end face to prevent leakage of fluid into said bore and between said shaft and said rotor.

2. For use in a high pressure pump of the rotary type, a rotor shaft, a rotor having a bore extending therethrough and removably received on said shaft, a portion of said rotor projecting beyond the end of said shaft and having a flat end face on the outer end thereof perpendicular to the axis of said shaft, means to prevent relative rotation between said shaft and said rotor, an enlarged threaded recess in the outer end of said bore, a sealing plug threadedly received in said recess and an annular flange on said plug engaging said end face to prevent leakage of fluid into said bore and between said shaft and said rotor.

3. For use in a high pressure pump of the rotary type, a rotor shaft, a rotor having a bore extending therethrough and removably received on said shaft, a portion of said rotor projecting beyond the end of said shaft and having a flat end face on the outer end thereof perpendicular to the axis of said shaft, means to prevent relative rotation between said shaft and said rotor, threads in the outer end of said bore, a sealing plug threadedly received in said bore and an annular flange on said plug engaging said end face to prevent leakage of fluid into said bore and between said shaft and said rotor.

4. For use in a high pressure pump of the rotary type, a rotor shaft, a rotor having a bore extending therethrough and removably received on said shaft, a portion of said rotor projecting beyond the end of said shaft and having an end face on the outer end thereof perpendicular to the axis of said shaft, means to prevent relative rotation between said shaft and said rotor, threads in the outer ends of said bore, a sealing plug threadedly received in said bore and an annular flange on said plug engaging said end face to prevent leakage of fluid into said bore and between said shaft and said rotor.

5. A structure as defined in claim 4 in which said plug is provided with means for automatically compensating for a variation in pressure tending to cause leakage between said rotor and said shaft and to vary the sealing effect in accordance with such change in pressure.
